(57) **ABSTRACT**

The present disclosure describes a case for portable electronic devices. According to various embodiments, a case may be capable of extending to accommodate different portable electronic devices. A discrete series of grooves within the case may provide the case with additional elasticity. A pattern of tessellations within the case may provide the case with additional elasticity. The increased elasticity may allow the case to be configured to frictionally engage and retain various portable electronic devices with slightly different physical dimensions.

EXTENDABLE, UNIVERSAL CASE FOR
PORTABLE ELECTRONIC DEVICES

RELATED APPLICATIONS

This application is a divisional of and claims priority to U.S. patent application Ser. No. 15/067,789 filed on Mar. 11, 2016, which claims priority to U.S. Patent Application Ser. No. 62/134,732 filed on Mar. 18, 2015 and U.S. Patent Application Ser. No. 62/201,399 filed on Aug. 5, 2015, all of which are incorporated herein by reference.

TECHNICAL FIELD

This disclosure generally relates to cases for portable electronic devices.

BRIEF DESCRIPTION OF THE DRAWINGS

Non-limiting and non-exhaustive embodiments of the disclosure are described, including various embodiments of the disclosure with reference to the figures, in which:

FIG. 1 is a rear view of an embodiment of a case with extendable corners.

FIG. 2 is a front perspective view of an embodiment of a case with extendable corners.

FIG. 3 is a front view of an embodiment of a case with extendable corners.

FIG. 4 is a front view of an embodiment of a case with one of the extendable corners slightly stretched.

FIG. 5 is a top-down view of the outside of an embodiment of a case with a tessellated structure, according to one embodiment.

FIG. 6A is an angled top-down view of the inside of an embodiment of a case with a second tessellated structure, according to one embodiment.

FIG. 6B is an angled top-down view of the inside of an embodiment of a case with a third tessellated structure, according to one embodiment.

FIG. 7 is a top-down view of the inside of an embodiment of a case with a tessellated structure, according to one embodiment.

In the following description, numerous specific details are provided for a thorough understanding of the various embodiments disclosed herein. The embodiments disclosed herein can be practiced without one or more of the specific details, or with other methods, components, materials, etc. In addition, in some cases, well-known structures, materials, or operations may not be shown or described in detail in order to avoid obscuring aspects of the disclosure. Furthermore, the described features, structures, or characteristics may be combined in any suitable manner in one or more alternative embodiments.

DETAILED DESCRIPTION

The present disclosure provides various embodiments of cases for securing and/or protecting portable electronic devices (PEDs). According to various embodiments, a case may be configured to secure PEDs having slightly different dimensions. This may accommodate the small physical variations typically observed when a manufacturer introduces an updated PED. For example, a single case may be configured to secure a first generation tablet device with a height of 9.5 inches, a width of 7.31 inches, and a depth of

2

0.37 inches, or a second generation tablet device with a height of 9.4 inches, a width of 6.6 inches, and a depth of 0.29 inches.

Such a case may comprise a body with a rear wall and a plurality of sidewalls coupled to the rear wall. These sidewalls and rear wall may be configured in size and shape to frictionally engage and retain a PED. The case may also have at least one discrete series of grooves in the rear wall. The discrete series of grooves may allow the rear wall to extend, and thus allow the case to accommodate slight variations in PED dimensions. In addition, the rear wall and sidewalls may be made of a material with a high elasticity coefficient further allowing the case to be stretch and accommodate tablets of different sizes.

A “portable electronic device” (PED) as used throughout the specification may include any of a wide variety of electronic devices. Specifically contemplated and illustrated are tablet-style electronic devices, including, but not limited to, electronic readers, tablet computers, tablet PCs, mini tablets, phablets, cellular phones (including smart phones), interactive displays, video displays, touch screens, touch computers, etc.

Additionally, any of a wide variety of materials and manufacturing methods may be used to produce the various components of the presently described case for portable electronic devices. For example, a case may utilize various plastics, rubbers, nylons, glasses, fabrics, leathers, and/or other suitable materials.

Reference throughout this specification to “one embodiment” or “an embodiment” means that a particular feature, structure, or characteristic described in connection with the embodiment is included in at least one embodiment. Thus, the appearances of the phrases “in one embodiment” or “in an embodiment” in various places throughout this specification are not necessarily all referring to the same embodiment.

The embodiments of the disclosure are described below with reference to the drawings, wherein like parts are designated by like numerals throughout. The components of the disclosed embodiments, as generally described and illustrated in the figures herein, could be arranged in and designed in a wide variety of different configurations. Furthermore, the features, structures, and operations associated with one embodiment may be applicable to or combined with the features, structures, or operations described in conjunction with another embodiment. In other instances, well-known structures, materials, or operations are not shown or described in detail to avoid obscuring aspects of this disclosure.

Thus, the following detailed description of the embodiments of the case is not intended to limit the scope of the disclosure, as claimed, but is merely representative of possible embodiments.

FIG. 1 is a rear view of an embodiment of a case 100 with extendable corners (i.e., first corner 102, second corner 104, third corner 106, and fourth corner 108). The case 100 may include a body 110, and several discrete series of grooves (e.g., first discrete series of grooves 112, second discrete series of grooves 114, third discrete series of grooves 116, and fourth discrete series of grooves 118). The grooves 112, 114, 116, and 118 may extend completely through the body 110. The grooves 112, 114, 116, and 118 may extend in a row equidistant from one another. The body 110 secures and/or protects PEDs while the discrete series of grooves 112, 114, 116, and 118 may selectively allow the corners 102, 104,

106, and 108 to extend. Thus, the case 100 may provide protection and/or support to PEDs with different dimensions by combining these elements.

The body 110 may include a rear wall 120 and sidewalls 122, 124, 126, 128. According to various embodiments, the rear wall 120 and sidewalls 122, 124, 126, 128 may provide protection for an encased PED. The rear wall 120 may comprise elastic materials to allow flexibility and stretchability. Other embodiments may include ornamental features, and may not even completely cover the backside of the PED. Yet other embodiments may have sidewalls composed of materials with a high elasticity coefficient. The stretchable sidewalls may assist in accommodating tablets of different sizes.

The body 110 may be configured to secure a variety of PEDs. The illustrated embodiment of the body 110 has a shape corresponding to a PED such that it engages the PED around its circumference to retain the PED in the case 100. Thus, the body 110 may use its sidewalls 122, 124, 126, 128 to secure a PED through a frictional engagement. Further, if the sidewalls 122, 124, 126, 128 have a high elasticity coefficient the sidewalls 122, 124, 126, 128 can have the ability to stretch and accommodate tablets of different sizes. The body 110 may use other mechanisms to secure the device such as elastics, magnets, adhesives, etc. The body 110 may secure a PED such that the backside and edges of the PED are substantially protected.

The discrete series of grooves may be in various positions. In one embodiment, the grooves are placed equidistant from one another in one or more rows. Thus, although two rows of grooves are shown, one, three or more rows may be utilized. As illustrated the discrete series or rows of grooves may be placed proximate to each corner and extend diagonally from the sidewalls. Alternatively, in another embodiment, the discrete series of grooves may be placed in parallel with the sidewalls.

FIG. 2 is a front perspective view of an embodiment of the case 100 with extendable corners. As shown, an embodiment of the body 110 may include a plurality of access points 212 for interacting with various elements of a PED. These elements vary by PED and may include, but are not limited to, a camera, USB port, headphone jack, power button, and volume rocker. Further, the body 110 may include a speaker grill 214 to prevent a PED's speaker from being muffled.

Further, the several discrete series of grooves (e.g., first discrete series of grooves 112, second discrete series of grooves 114, third discrete series of grooves 116, and fourth discrete series of grooves 118) may appear on the front of the case 100. For example, as illustrated, the discrete grooves 112, 114, 116, and 118 may have holes that extend completely through the body 110.

Another embodiment may have the discrete grooves 112, 114, 116, and 118 only partially extended into the body 110. For example, the discrete series grooves 112, 114, 116, and 118 may be shallow divots formed along the front of the case 100. In such an embodiment, the discrete grooves 112, 114, 116, and 118 would not appear on the back of the case 100. Another embodiment may have shallow divots along the back of the case 100 forming the discrete series of grooves 112, 114, 116, and 118.

FIGS. 3-4 illustrate various front views of an embodiment of the case 100 with extendable corners. As demonstrated, each corner (e.g., the corner 106) may extend between a contracted position, as shown in FIG. 3, and an extended position, as shown in FIG. 4. The corners may be extended by an exertion of physical force of the user, and may remain in the extended position if a PED is inserted in the case 100.

The discrete series of grooves may aid in allowing the corners to extend. As illustrated in FIG. 3, the discrete series of grooves 116 may be thin slits when the corner 106 is in a contracted position. As the user extends the corner 106, the discrete series of grooves 116 may expand as illustrated in FIG. 4. The discrete series of grooves 116 may cause the case 100 to be more flexible or stretchable along that area. Thus, much of the extending may be directly along the discrete series of grooves 116. In some embodiments the case 100 may be made of material that has a greater elasticity in order to allow the case 100 to extend even further.

This ability to extend may allow the case 100 to accommodate PEDs of different dimensions. Many PED manufacturers in an attempt to improve their PED adjust different parameters of their PED when they introduce a new generation of the same PED. Often the physical dimensions are among those parameters that are adjusted. In these situations, the extended corners may allow the case 100 to fit both the original PED and the new generation PED. For example, the case 100 may be made with such dimensions that it fits a PED in the extended position. If the manufacturer were to release another PED that is slightly smaller, the case 100 may be able to fit that PED in its contracted position. Similarly, case 100 may be made with such dimensions that it fits a PED in the contracted position. If the manufacturer were to release another PED that is slightly larger, the case 100 may be able to fit that PED in its extended position.

FIG. 5 is a top-down view of the outside of an embodiment of a case 500 with a tessellated structure. As shown in FIG. 5, the case 500 may have a rear wall 502 and four sidewalls 504, 506, 508, and 510 for partially or entirely encasing a PED. The case 500 may include a reinforcing member 520. FIG. 5 also shows the case 500 with a tessellation of apertures 530. The apertures 530 are embodied as a three-pointed star shape. The tessellation of apertures 530 in the case 500 may cover all or part of the case 500, including all or part of one or more of the rear wall 502 and four sidewalls 504, 506, 508, and 510, and may provide aesthetic appeal as well as increased flexibility and elasticity. This increased flexibility and elasticity may assist fitting PEDs of different sizes inside the case 500 as well as provide increased durability and/or longevity to the case 500. The case 500 secures and/or protects PEDs while the reinforcing member 520 may be stretchable to allow the reinforcing member 520 to expand or contract to selectively allow the case 500 to fit PEDs of varying sizes (e.g., PEDs of different product generations). In other embodiments, the reinforcing member 520 may not expand or contract but rather the tessellated body portion (which may include the rear wall 502 and the four sidewalls 504, 506, 508, and 510) of the case 500 may expand or contract to selectively allow the case 500 to fit PEDs of varying sizes. Thus, the case 500 may provide protection and/or support to PEDs with different dimensions by combining these elements. The case 500 may also include a center aperture 540 in the reinforcing member 520, which allows a user to view a PED in the case 500 from the backside of the case 500.

According to various embodiments, the case 500 may provide protection for an encased PED. Other embodiments may include ornamental features including but not limited to the tessellation of aperture 530 shown in FIG. 5, and may not even completely cover the backside of the PED. Yet other embodiments may have the reinforcing member 520 composed of materials with a high elasticity coefficient. The stretchable reinforcing member 520 may assist in accommodating PEDs of different sizes. Some embodiments may

have a rear wall 502 and four opposing sidewalls 504, 506, 508, and 510, while other embodiments may have fewer than four sidewalls.

In some embodiments, the rear wall 502 and the opposing sidewalls 504, 506, 508, and 510 may be configured to elastically adjust in size and shape to fit PEDs of different sizes. For example, the rear wall 502 may be coupled to each of the four opposing sidewalls 504, 506, 508, and 510 that frictionally engage and secure a PED. The case 500 may be made partially or entirely of elastic material, thus accommodating PEDs of different sizes. Another embodiment may have tessellations like those shown in FIG. 5 within the body of the case 500 that allow for further elasticity and malleability as well as aesthetic appeal. The tessellations shown in FIGS. 5, 6A, 6B, and 7 are possible patterns that could be used, though any number of other patterns are also contemplated. In some embodiments the case 500 may be made of material that has a greater elasticity in order to allow the case 500 to extend even further.

This ability to extend may allow the case 500 to accommodate PEDs of different dimensions. Many PED manufacturers, in an attempt to improve their PEDs, adjust different parameters of their PED when they introduce a new generation of the same PED. Often the physical dimensions are among those parameters that are adjusted. In these situations, the expandable sidewalls 504, 506, 508, and 510 and/or elastic rear wall 502 may allow the case 500 to fit both the original PED and the new generation PED. For example, the case 500 may be made with such dimensions that it fits a PED in the extended position. If the manufacturer were to release another PED that is slightly smaller, the case 500 may be able to fit that PED in its contracted position. Similarly, the case 500 may be made with such dimensions that it fits a PED in the contracted position. If the manufacturer were to release another PED that is slightly larger, the case 500 may be able to fit that PED in its extended position.

The case 500 may be configured to secure a variety of different PEDs. The illustrated embodiment of the case 500 has a shape corresponding to a PED such that it engages the PED around its circumference to retain the PED in the case 500. Thus, the case 500 may use its sidewalls 504, 506, 508, and 510 and the reinforcing member 520 to secure a PED through a frictional engagement. Further, if the reinforcing member 520 has a high elasticity coefficient, the sidewalls 504, 506, 508, and 510 can have the ability to adjust position as the reinforcing member 520 stretches, to accommodate PEDs of different sizes. The case 500 may use other mechanisms to secure the device such as elastics, magnets, adhesives, etc. The case 500 may secure a PED such that the backside and edges of the PED are substantially protected.

In some embodiments, the case 500 may include a plurality of access points (not shown) for interacting with various elements of a PED. For example, the case 500 may include access points within one or more of the sidewalls 504, 506, 508, and 510, the reinforcing member 520, and/or the rear wall 502. These elements vary by PED and may include, but are not limited to, a camera, USB port, headphone jack, power button, and volume rocker. Further, these elements will vary in size and location on each different PED. Thus, the access points of the case 500 may be sized and/or positioned to allow for access to the elements of various PEDs of different dimensions, though not each PED will fit exactly the same.

FIG. 6A is an angled top-down view of the inside of an embodiment of a case 600 with a second tessellated structure, according to one embodiment. As shown in FIG. 6A,

the case 600 may have a tessellation pattern using a three-pointed star shape with a wide spacing or sparse placement. The tessellations may occur in all or part of the rear wall 502 (FIG. 5), the reinforcing member 520 (FIG. 5), and/or the sidewalls 504, 506, 508, 510 (FIG. 5).

FIG. 6B is an angled top-down view of the inside of an embodiment of a case 650 with a third tessellated structure, according to one embodiment. FIG. 6B shows the case 650 with tessellations using a hexagonal pattern with a tighter spacing or dense placement. Different shapes, spacing, and/or densities of the tessellation patterns may provide for varying degrees of flexibility and/or elasticity of the case 650, thereby enabling the case 650 to fit PEDs of varying sizes.

It is noted that while only three patterns are depicted, various others are contemplated. Tessellations of different sizes, patterns, shapes, and spacing may provide varying degrees of flexibility and elasticity to assist fitting PEDs of different sizes and are within the scope of this description.

FIG. 7 is a top-down view of the inside of an embodiment of a case 700 with a tessellated structure, according to one embodiment. As shown, FIG. 7 illustrates an embodiment of the case 700 having a closely fit tessellation pattern using a three-pointed star shape. Also shown in FIG. 7 is a reinforcing member 720 with one possible design, though various other designs incorporating any number of different shapes and features are also contemplated. The reinforcing member 720 may be stretchable and disposed to render one or more tessellations incomplete. The reinforcing member 720 may include a center aperture 722 to allow a user to view the PED from a backside of the case 700 while the PED is in the case 700. The reinforcing member 720 may include one or more apertures 724 to facilitate stretching of the reinforcing member 720.

The above description provides numerous specific details for a thorough understanding of the embodiments described herein. However, those of skill in the art will recognize that one or more of the specific details may be omitted, or other methods, components, or materials may be used. In some cases, operations are not shown or described in detail. Additionally, features or elements described in conjunction with any one embodiment may be adapted for use with and/or combined with the features of any other embodiment.

What is claimed:

1. A case for a portable electronic device, the case comprising:
a rear wall configured to expand to accommodate portable electronic devices of different size, the rear wall including four corners;
first, second, third, and fourth sidewalls coupled to the rear wall, wherein the sidewalls and the rear wall are configured in size and shape to frictionally engage and retain a portable electronic device;
a first discrete series of unobstructed apertures disposed in the rear wall and extending in a first row diagonally between positions adjacent the first and second sidewalls;
a second discrete series of unobstructed apertures disposed in the rear wall and extending in a second row diagonally between positions adjacent the second and third sidewalls;
a third discrete series of unobstructed apertures disposed in the rear wall and extending in a third row diagonally between positions adjacent the third and fourth sidewalls; and

a fourth discrete series of unobstructed apertures disposed in the rear wall and extending in a fourth row diagonally between positions adjacent the fourth and first sidewalls,

wherein the first, second, third, and fourth rows do not intersect one another and wherein the apertures in each row are disposed equidistant from one another.

2. The case of claim 1, wherein the first, second, third, and fourth discrete series of apertures further includes disposing apertures parallel to one another in the same row.

3. The case of claim 1, wherein the first sidewall includes a sidewall aperture to facilitate access to the portable electronic device.

4. The case of claim 1, wherein the rear wall comprises, an elastic portion, wherein the first, second, third, and fourth series of apertures are disposed in the elastic portion, and

a reinforcing member including a different material than the elastic portion.

5. The case of claim 4, wherein the elastic portion surrounds the reinforcing member.

6. The case of claim 4, wherein the reinforcing member is rigid and substantially inelastic.

7. The case of claim 4, wherein the reinforcing member includes an elastic material.

8. The case of claim 4, wherein the reinforcing member further comprises a center aperture extending through the rear wall.

9. A case for a portable electronic device, the case comprising:

a rear wall including an elastic material configured to expand to accommodate portable electronic devices of different size, the rear wall including four corners; first, second, third, and fourth sidewalls coupled to the rear wall, wherein the sidewalls and the rear wall are configured in size and shape to frictionally engage and retain a portable electronic device;

a first discrete series of unobstructed apertures disposed in the rear wall and extending diagonally in a first line from a first location proximate to the first sidewall to a second location proximate to the second sidewall;

a second discrete series of unobstructed apertures disposed in the rear wall and extending diagonally in a second line from a first location proximate to the second sidewall to a second location proximate to the third sidewall;

a third discrete series of unobstructed apertures disposed in the rear wall and extending diagonally in a third line from a first location proximate to the third sidewall to a second location proximate to the fourth sidewall; and

a fourth discrete series of unobstructed apertures disposed in the rear wall and extending diagonally in a fourth line from a first location proximate to the fourth sidewall to a second location proximate to the first sidewall,

wherein the first, second, third, and fourth lines do not intersect one another and are equivalent in length.

10. The case of claim 9, wherein the apertures in each line are disposed equidistant from one another.

11. The case of claim 9, wherein the first, second, third, and fourth discrete series of apertures further includes disposing apertures parallel to one another in the same row.

12. The case of claim 9, wherein the first sidewall includes a sidewall aperture to facilitate access to the portable electronic device.

13. The case of claim 9, wherein the rear wall comprises, an elastic portion, wherein the first, second, third, and fourth series of apertures are disposed in the elastic portion, and a reinforcing member including a different material than the elastic portion.

14. The case of claim 13, wherein the elastic portion surrounds the reinforcing member.

15. The case of claim 13, wherein the reinforcing member is rigid and substantially inelastic.

16. The case of claim 13, wherein the reinforcing member includes an elastic material.

17. The case of claim 13, wherein the reinforcing member further comprises a center aperture extending through the rear wall.

18. A case for a portable electronic device, the case comprising:

a rear wall configured to expand to accommodate portable electronic devices of different size, the rear wall including four corners;

first, second, third, and fourth sidewalls coupled to the rear wall, wherein the sidewalls and the rear wall are configured in size and shape to frictionally engage and retain a portable electronic device;

a first discrete series of unobstructed apertures disposed in the rear wall and extending in a first row diagonally between positions adjacent the first and second sidewalls;

a second discrete series of unobstructed apertures disposed in the rear wall and extending in a second row diagonally between positions adjacent the second and third sidewalls;

a third discrete series of unobstructed apertures disposed in the rear wall and extending in a third row diagonally between positions adjacent the third and fourth sidewalls; and

a fourth discrete series of unobstructed apertures disposed in the rear wall and extending in a fourth row diagonally between positions adjacent the fourth and first sidewalls,

wherein the first, second, third, and fourth rows do not intersect one another and wherein the apertures each have a length, extending along a respective row, greater than their width.
